CLAIM

The ornamental design for a peristaltic infusion pump, as shown and described.

DESCRIPTION

FIG. 1 is a front elevational view of our new peristaltic infusion pump, with the swing arm portion of the invention in the closed position;

FIG. 2 is a rear elevational view thereof, with the swing arm portion of the invention in the closed position;

FIG. 3 is a top elevational view thereof, with the swing arm portion of the invention in the closed position;

FIG. 4 is a bottom plan view thereof, with the swing arm portion of the invention in the closed position;

FIG. 5 is a right side elevational view thereof, with the swing arm portion of the invention in the closed position;

FIG. 6 is a left side elevational view thereof, with the swing arm portion of the invention in the closed position;

FIG. 7 is a front elevational view thereof, with the swing arm portion of the invention in an open position;

FIG. 8 is a top elevational view thereof, with the swing arm portion of the invention in an open position;

FIG. 9 is a right side elevational view thereof, with the swing arm portion of the invention in an open position;

FIG. 10 is a left side elevational view thereof, with the swing arm portion of the invention in an open position;

FIG. 11 is a bottom plan view thereof, with the swing arm portion of the invention in an open position;

FIG. 12 is a perspective view thereof, with the swing arm portion of the invention in a closed position; and,

FIG. 13 is a perspective view thereof, with the swing arm portion of the invention in an open position.
